(57) **CLAIM**

The ornamental design for a grille for vehicle or replica thereof, as shown and described.

DESCRIPTION

FIG. 1 is an enlarged, partial front left perspective view of a grille for vehicle or replica thereof in accordance with the present design.

FIG. 2 is a front elevation view thereof.

FIG. 3 is a left elevation view thereof.

FIG. 4 is a front left perspective view thereof.

FIG. 5 is a top plan view thereof; and,

FIG. 6 is an enlarged, partial left elevation view thereof. The portions of the grille for vehicle or replica thereof shown in evenly spaced broken lines depict environmental structures that form no part of the claim. Portions of the grille for vehicle or replica thereof shown in dot-dash lines depict an unclaimed boundary between claimed and unclaimed portions of the grille for vehicle or replica thereof.

1 Claim, 6 Drawing Sheets
